SPLIT-END BEARING PILE

Ulrich W. Stoll, Vanderbilt Drive, Oxnard, Calif.

Filed June 4, 1954, Ser. No. 434,687

2 Claims. (Cl. 61—53)

(Granted under Title 35, U.S. Code (1952), sec. 266)

The invention described herein may be manufactured and used by or for the Government of the United States of America for governmental purposes without the payment of any royalties thereon or therefor.

This invention relates to a pile having its lower end or base formed to be expanded after the pile is driven into the ground.

In a preferred embodiment, the pile, in the form of a metal tube having pre-weakened sections provided with radial fins, is provided with an inner drive rod which takes most of the driving stress. The drive rod is provided with a separable plug to facilitate penetration into the soil, and has a tapered shoulder portion of greater diameter than the tube. When the pile has been driven to the desired depth, the drive rod is withdrawn and the pile driving hammer is applied directly to the tube, causing the lower end of the tube, with its attached fins, to be spread outwardly to form an expanded base capable of sustaining great bearing loads.

It is an object of the invention to provide a pile having high pulling resistance and load supporting capacity.

A further object of the invention is to provide an improved pile of simple design and economical to manufacture and install.

Other objects and many of the attendant advantages of this invention will be readily appreciated as the same becomes better understood by reference to the following description.

Fig. 1 is a view in longitudinal section of a pile embodying the invention;

Fig. 2 is an enlarged view in elevation of the lower end of the pile in unexpanded condition;

Fig. 3 is a sectional view taken on the line 3—3 of Fig. 2;

Fig. 4 is a sectional view taken on the line 4—4 of Fig. 2;

Fig. 5 is a view in elevation of the pile with its lower end in partially expanded condition; and

Fig. 6 is a similar view showing the base fully expanded.

The pile shown in the drawing consists of a pipe or tube 10 having its lower end formed with a plurality of longitudinal slots 12 which divide the tube into a number of segments 14. To each segment is secured as by welding a fin 16 having a tapered forward end 18 and an inclined rear edge 20 designed to rest against the periphery of the tube when the lower end or base of the tubular pile is expanded. In order to facilitate bending of the segments in the expanding operation, it is advisable to form a portion 22 of the tube to a square section, as shown in Figs. 2 and 3, the lower end of the tube remaining cylindrical as shown in Fig. 4.

For the driving operation, a driving rod 30 is provided for insertion in the tube 10 and is formed at its upper end with an enlarged cap 32 which extends over the top of the tube to transmit driving force thereto. In the lower end of the tube 10 is placed a penetrating member or plug 34 having a lower surface 36 in conical form

2

to facilitate penetration of the soil, an upper conical surface or shoulder 38 designed to exert a cam action on segments 14 and fins 16, and a shank 40 designed to receive driving force from driving rod 30. The plug 34 is preferably made of concrete.

In order to emplace the pile, the plug 34 and drive rod 30 are inserted in place in heavy walled tube or pipe 10 as shown in Fig. 1 and driving blows are applied to the cap 32. Because the shell or tube 10 meets little resistance, the major force of the pile driving hammer is taken by the rod 30, which transmits the force to the plug 34. When the pile is driven nearly to the desired depth, the driving rod 30 is withdrawn, and hammer blows are applied directly to the upper end of the tube 10. The lower ends of segments 14 then impinge forcefully upon the surface 38 of the relatively stationary plug 34, which acts as a cam in forcing them outwardly as indicated in Fig. 5, bending of the tube material occurring in the square section 22 at the base of the fins 16. After the pile has been thus driven through a predetermined distance, the edges 20 of the fins will have been moved into contact with the outer wall of the tube 10, and the base will be fully expanded as shown in Fig. 6. The plug 34 remains as a permanent part of the expanded base.

It will be seen that the movement of fins 16 from the positions shown in Fig. 1 to the positions shown in Fig. 6 involves but little lateral displacement of the soil. Moreover, as the segments 14 are moved downwardly and outwardly, their undersides act to consolidate and compact the underlying soil generally indicated at 44 in Fig. 6. The expanded base, of which plug 34 forms a part, has an area which enables the pile to sustain loads many times in excess of the capacity of a pile without such base, this effect being heightened by the arrangement of the segments, which to some degree enclose or confine a mass of soil. It is not necessary to fill the tube 10 with concrete in order to increase its bearing area, that function being performed by plug 34. As may be noted, obviously fins 16 prevent the tube 10 from turning or rotating as it is being driven into the bearing strata and prevent its rotation after being driven into place.

Obviously many modifications and variations of the present invention are possible in the light of the above teachings. It is therefore to be understood that within the scope of the appended claims the invention may be practiced otherwise than as specifically described.

What is claimed is:

1. The method of driving a high compression load bearing pile, which method comprises:
  - 50 disposing a plug in the ground at the location where the pile is to be driven, said plug having a driving point adapted to enter the ground, a cylindrical shank portion with a driving top substantially normal to the axis of said plug, a central cylindrical section of greater diameter than said shank portion, and an inwardly tapered conical shoulder connecting said central cylindrical portion and said cylindrical shank;
  - 55 disposing the bottom end of a vertical heavy walled tube over the cylindrical shank portion of said plug and permitting the said bottom end of said tube to rest on said inwardly tapered conical shoulder of said plug, said tube having a plurality of longitudinal slots formed in the bottom end of said tube, an equal plurality of segments formed in said bottom end of said tube by said slots, means in said tube at the upper end of said segments for facilitating the outward bending of said segments, radial heavy sheet metal fins secured to said segments, said radial fins having outer edges tapering outwardly and upwardly from said segments and upper edges disposed at an acute angle to the wall of said vertical tube;
  - 60 inserting a driving rod into said vertical heavy walled

70 tube;

tube, said driving rod being of a diameter substantially equal to the inner diameter of said tube and resting on the driving top of said plug, said driving rod having an enlarged driving cap at its upper end which rests on the top of said tube;

applying a driving force to said driving cap whereby said plug and said heavy walled tube are driven into the ground strata the desired distance, the major portion of said driving force being primarily applied to said driving rod and said plug, and only sufficient driving force being applied to said tube to cause it to follow said plug against the minor resistance encountered by the passage of said radial fins through said ground strata;

removing said driving rod from said tube;

applying driving force to the top of said tube whereby the bottom portion of said tube is driven downwardly past said plug, forcing said segments and radial fins downwardly and outwardly substantially beyond the diameter of said central cylindrical portion of said plug until the upper edges of said radial fins abut against the cylindrical wall of said vertical tube adjacent the upper ends of said segments thereby limiting the further outward bending of said segments and transmitting the compressive load reaction forces acting vertically upward under said segments to said heavy walled vertical tube whereby said plug, said outwardly bent segments, and said radial fins comprise a non-rotative maximum compression load supporting base for said pile.

2. A high compression load bearing pile comprising in combination:

a heavy walled cylindrical metal tube of sufficient length to form a load bearing pile after being driven into a load bearing ground strata;

a plurality of longitudinal slots formed in the lower end of said tube to provide an equal plurality of segments;

means located at the upper ends of said segments for facilitating their bending outwardly as said pile is driven downwardly;

means associated with each of said segments for limit-

ing the outward bending of said segments, said means being adapted to support a compressive load between each of said segments and the wall of said tube adjacent to the upper end of said segments and comprising a longitudinally extending radial fin secured to each segment, each fin increasing in radial extent in an upward direction and having an upper edge disposed at an acute angle to said tube; and

separable ground penetrating plug means inserted in the lower end of said heavy walled metal tube and forcing said segments to bend outwardly into said ground strata until said compressive load means associated with said segments abut against the outer surface of the said tube as the lower end of said tube is driven downwardly over and past said ground penetrating means, said plug means comprising a cylindrical shank adapted to be inserted into the lower end of said tube, a conically pointed lower end adapted to penetrate said ground strata, a central cylindrical section having a diameter greater than the external diameter of said tube and an inwardly tapered conical section joining said central section and said shank further characterized by making the acute angle formed between the upper edge of said radial fin and the wall of said tube substantially equal to the angle of the inwardly tapered conical section joining said central section and said shank of said plug with the longitudinal axis of said shank.
